Eleanor F. May of Lowell, Mass.

Assignor to

The Lowell Manufacturing Company of the same place

Letters Patent No. 2009 Dated Dec. 13, 1871.

Design for a Carpet Pattern.

The schedule referred to in these Letters Patent and making part of the same.

It all whom it may concern:

Be it known that I, Eleanor F. May, of Lowell, in the County of Middlesex and State of Massachusetts, have invented and designed a new pattern for carpets or other fabrics, of which the following is a full, clear and exact description, reference being had to the accompanying drawings, making part of this specification.

A is a cross-shaped figure resting on the Persian styled figure B.

C, C, C are scrolls which surround ground D, said ground being composed of small leaves and sprigs.

Centre E is composed of four shells and a rosette surrounded by scrolls find C, 1, 2 and 3 when matched will form a centre like E, 4 and 6.

4, 4 are wreaths composed of oak leaves and acorns.
5, 5, 5 and 5 are halves of wreaths similar to 4, 4, 6, 7 and 8, when matched will form a centre like A, B and D.
